UNITED STATES PATENT OFFICE.

GEORGE MALCOLM TURNER, OF SOUTH KENSINGTON, LONDON, ENGLAND.

MAGNETO-ELECTRIC MACHINE.

Application filed July 19, 1920. Serial No. 397,481.

(GRANTED UNDER THE PROVISIONS OF THE ACT OF MARCH 3, 1921, 41 STAT. L., 1313.)

To all whom it may concern:

Be it known that I, GEORGE MALCOLM TURNER, a subject of the King of Great Britain and Ireland, and a resident of South Kensington, county of London, England, have invented a certain new and useful Improvement in the Construction of Magneto-Electric Machines, for which I have obtained Letters Patent in Great Britain, No. 142,177, dated Jan. 28, 1919, and of which the following is a specification.

This invention relates to improvements in magneto-electric machines of the type particularly adapted for use in connection with internal combustion motors.

One of the objects of the present invention is to provide means whereby several simultaneous and independent currents may be obtained from a single magneto for synchronous ignition, thereby gaining full benefit of each spark during the firing stroke of the motor and thereby increasing the horsepower of the engine by complete combustion of the fuel. Heretofore in order to obtain effective synchronous sparking, it has been the practice to use either separate synchronized magnetos or else two sparks in series, which can produce only half the desired heating effect.

Accordingly, the present invention proposes to obviate the necessity of using synchronized magneto machines for the obtaining of synchronized ignition, and in that connection eliminate the losses due to incorrect timing on account of the creeping out of step of the two synchronized magneto machines.

Having thus declared the nature and objects of this invention, the manner in which this is to be performed is to make use of a magneto electric generator. This generator being composed of coils, such that they comprise a primary and secondary winding, in which current is generated in the usual manner, by means of the use of permanent magnetic fields, and increased in a well known manner by the action of a circuit breaker, or the like, and condenser.

From such machines I am able to obtain sparks as desired by arranging details to take advantage of the fact that in each of the component coils placed as herein indicated, a separate "current peak" is generated, accompanied by accurate timing, both induction and timing being further empha-

sized by the action of the circuit breaker, or the like. These "current peaks" may be utilized separately and individually as desired, distribution being suitably effected by means of a rotary disc form of distributor or collector. One such, an inductor salient pole machine, is herein shown and explained in detail.

Heretofore but one attempt has been made to obtain more than one independent spark from a single machine, with the use of a bipolar field, and an interrupting device, and that employed a double T-wound Sims rotary armature with "grounded" windings and circuit breaker, and distributor of two segments at 90 degrees apart, as a distributing device therefor, the whole forming an apparatus for supplying current for the ignition of four-cylinder engines, and to this arrangement I make no claim.

I am aware that multipolar induction magnetos have been developed for ignition purposes, without the use of an interrupter device, relying only on a transformer action to generate a high potential, and to the breaking down point of the spark gap resistance, or else the "magnetic break" for timing purposes, and to these I make no claim.

I am also aware that a multipolar inductor magneto has been produced for wireless and field telegraph, and to this I make no claim.

In the accompanying drawings, which are to be regarded as diagrammatic,

Figure 1 is a diagrammatic view showing (partly in section) the relative arrangement of parts of the present magneto construction.

Figure 2 is a diagrammatic end elevation, the line A—B therein indicating the line of section for the sectional portion of Figure 1.

Figures 3, 4, 5 and 6 are diagrammatic views showing the path of the flux.

Figure 7 is a detail diagram of the stationary distributor and brush arrangement.

Figure 8 is a diagram showing the ignition connections for a two-cylinder engine.

Similar reference characters designate corresponding parts in the several figures of the drawings.

In Figure 1; C, B, H represents a contact breaker; R, B, H ball-race housing; S, shaft. D, distributor (stationary); I, T insulated high tension terminal connections; B, brush; T, collector, or collecting device; D, C dust

cover; M, magneto; C, L cross laminations; C, I coil; C, I, S section of coil 1; P.1 pole 1 of magnet M; P.2 pole 2 of magnet M as illustrated both solid salient poles; C, I, P,

5 T, cast iron or laminated pole tips; D, B, R, H, driving end plate ball race housing; I inductor laminations or magnetic conductor segments.

In Figure 2 these letters correspond; in 10 addition P^3 and P^4 represent the poles of the magnet M^2 in section; C^1 , C^2 , C^3 , C^4 stationary armature coils in which the currents are generated, and which may be placed as desired, and used as required in conjunction 15 with a circuit breaker, rotor and the like, or as shown. I cast iron or laminated inductors; A, C inductor or rotor core, in this arrangement (as shown) of non-magnetic metal.

20 Figures 3, 4, 5 and 6 of the drawings show the flux path which, starting from pole N of magnet P^2 (Figures 3 and 5), goes to pole tips C, I, P, T, then through segment I (Figure 5) to other pole tips L, then enters 25 core of coil C^1 and thence into the cross laminations CL of pole tips L, as shown in Figure 4. From the core of coil C^1 of L, the flux enters the cross laminations CL which provide the path to the core of coil C^4 (see 30 Figure 4), then it passes through core of the coil C^4 to the rotor end where it enters pole tips L for C^4 (see Figures 3 and 5), thence around to pole N.

Similarly, the separate "path of the flux" 35 from M^2 can be followed, and the "alternations" or "fluctuations" caused by the "inductor" are clear. This movement of the "lines of force" generates in the coils an "electro-motive force" in the usual well 40 known manner.

Figures 4 and 7 illustrate coils in the background, the same being designated C^1 , C^2 , C^3 , and C^4 . Coil C^1 is shown connected in series with C^2 by high tension lead L^a , and 45 coil C^3 and C^4 are shown connected by the lead L^{a1} .

Also high tension leads HTL are shown in dotted lines connecting each coil to the segment S_t. In this arrangement the segments are shown connected in multiple and arranged at angles of 45°.

The stationary distributor, STD, is shown more in detail in Figure 7 of the drawings and in Figure 1 is indicated by the line 55 appearing between parts T and CL. In Figure 7, T the collecting device, is shown with two brushes B collecting and distributing through to D, as indicated by Figure 1. In the particular arrangement shown these 60 two brushes B are shown as set diagonally opposite each other, though it will of course

be understood that the actual arrangement of brushes is dependent upon the relative speeds of the magneto and engine, and other details.

The adaptation of the type of fields herein shown and explained for the purposes of generating currents suitable for high and low tension ignition, for charging batteries, lighting, signalling, and other purposes, is 70 obvious; and although I show a special adaptation of a two magnet horse-shoe field, I may make a similar salient field of three or more separate horse-shoe magnets; or I may connect the yokes of P^2 to P^3 ; and P^1 to P^4 , thus forming an alternative multipolar field, in a convenient manner, of any desired cross-section and number of poles.

The wiring and timing diagram of Figure 8 shows the connections and how the current peaks may be utilized for synchronous ignition.

Figure 8 shows the general character of the case under consideration, a single contact breaker c^8 and condenser c being shown. 85 In this figure the primary is designated as x the high tension coil designated as y and the connections leading to cylinder No. 1 are designated as z^1 and the connections leading to cylinder No. 2 are designated as z^2 .

I claim:-

A multi-polar inductor magneto-electric machine including permanent multi-polar horse shoe magnets having cast iron salient pole tips, stationary high and low tension coils wound on laminated cores and arranged alternately with respect to the salient pole tips of the magnets and parallel to, and within, the legs of the magnets, a shaft parallel to said laminated cores and the legs of the magnets, an inductor having laminated multi-segments rotatably mounted on said shaft within the space formed by said coils and pole tips, cross laminations mounted concentrically on said shaft within and 105 across the arch of the magnets, whereby the magnetic flux returning within the legs of the magnets will traverse the core laminations and cross laminations by way of the inductor segments and pole tips, a stationary 110 distributor arranged on said shaft adjacent said cross laminations, insulated high tension terminal connections for said distributor, a collector device carried by the shaft and having brushes engaging said distributor, a circuit interrupter device externally mounted on the arch of said magnets and connected with the end of the shaft projecting through said arch.

In testimony whereof I have affixed my signature hereto this fifth day of July, 1920.

GEORGE MALCOLM TURNER.
